CLAIM

The ornamental design for a splash guard/bowl stand, as shown and described.

DESCRIPTION

FIG. 1 is a top perspective view of the splash guard/bowl stand showing our new design;

FIG. 2 is an inverted perspective view thereof;

FIG. 3 is a side elevation view thereof, all side elevations being the same;

FIG. 4 is a top plan view thereof;

FIG. 5 is a bottom plan view thereof; and,

FIG. 6 is a cross section view taken along line 6—6 in FIG. 4.

The broken line showing of a bowl in FIGS. 1 and 2 are for illustrative purposes only and forms no part of the claimed design.
